US00D969821S

(12) **United States Design Patent** (10) Patent No.: **US D969,821 S**
Scriven et al. (45) Date of Patent: **** Nov. 15, 2022**

(54) **DISPLAY SCREEN OR PORTION THEREOF
WITH A GRAPHICAL USER INTERFACE**

(71) Applicant: **DIALS, LLC**, Dover, DE (US)

(72) Inventors: **Thomas Scriven**, Los Angeles, CA (US); **Dante Orpilla**, San Diego, CA (US)

(73) Assignee: **DIALS, LLC**, Dover, DE (US)

(**) Term: **15 Years**

(21) Appl. No.: **29/735,673**

(22) Filed: **May 22, 2020**

Related U.S. Application Data

(63) Continuation of application No. 14/558,667, filed on Dec. 2, 2014, now abandoned.

(51) **LOC (13) Cl.** **14-04**

CLAIM

The ornamental design for a display screen or portion thereof with a graphical user interface, as shown and described.

DESCRIPTION

The sole FIGURE is a front view of a display screen or portion thereof with a graphical user interface showing our new design.

The outermost broken lines illustrate a device, or portion thereof, and edges of a display screen, or portion thereof, and form no part of the claimed design. The remaining broken lines illustrating portions of the graphical user interface, form no part of the claimed design.

1 Claim, 1 Drawing Sheet
